BY

UNITED STATES PATENT OFFICE.

ERNEST S. GOLDY, OF HADDONFIELD, NEW JERSEY.

TOOTH-BRUSH.

1,134,450.

Specification of Letters Patent.

Patented Apr. 6, 1915.

Application filed November 20, 1913. Serial No. 802,035.

To all whom it may concern:

Be it known that I, ERNEST S. GOLDY, a citizen of the United States, and a resident of Haddonfield, in the county of Camden, State of New Jersey, have invented certain new and useful Improvements in Tooth-Brushes and the like, of which the following is a specification, reference being had to the accompanying drawing.

10 This invention especially relates to that class of tooth brushes in which the brush-head is adapted to be detached from its operative position upon the handle and enclosed within the latter when not in use, and 15 among the principal objects of my invention are to provide an improved means for securely attaching the brush-head to the handle when in operative position thereon, and to provide a means of attachment or 20 locking means which shall prevent both longitudinal and rotative movement of the brush-head with respect to the handle, and which shall be of such nature as to be readily and quickly operated.

25 Further objects of my invention are to provide a means for attaching the brush-head to the handle which shall be neat and efficient and which may be readily constructed and at a minimum expense.

30 My invention further includes all of the various other objects and novel features of construction and arrangement hereinafter more definitely specified.

In the accompanying drawing, in which 35 one form of my invention is illustrated, Figure 1 is a side elevation of the brush-head and handle in operative position: Fig. 2 is a side elevation of the handle, the brush-head being shown in broken lines disposed 40 within the handle; Fig. 3 is a top plan view of the brush-head; Fig. 4, an end view of the handle with the parts substantially in the position shown in Fig. 2; Fig. 5 is an 45 end view of a portion of the locking means removed from the handle; and Fig. 6, a side elevation of the brush-head, partially in central vertical section.

Referring to the drawing, the handle 1 of the device may be formed, preferably in approximately the shape indicated, of celluloid, Parisian ivory, sheet metal, or any other suitable material and may be so shaped and of such a size as to readily contain the

brush-head when not in use, as shown in Fig. 2. The lower part of the handle at one end, may preferably be extended somewhat beyond the main portion thereof to form a cylindrical projection 2, hereinafter termed the "socket" the central longitudinal axis of which may preferably be approximately co-incident with the plane of the surface of the interior of the bottom portion of the handle, although this is not essential. The socket 2 may be formed in any desired manner and preferably integral with the rest 60 of the handle. In practice, however, it has been found that the flat sheet from which the handle is generally made may be readily shaped in such manner that when the handle is formed up, the socket 2 may be formed 65 at the same time and with a minimum of operations and expense. Of course if the handle is molded or otherwise made from some plastic composition instead of from a flat sheet of material, the mold may be so 70 constructed as to produce the desired form, or, if desired, the socket 2 may be formed separately from the body of the handle, and united thereto in any suitable manner, as 75 by solder or cement.

The brush-head 5, having the usual bristles 6, may also be constructed of any desired material, although celluloid, Parisian ivory, or similar compositions are well fitted for this purpose. The brush-head may be provided with a suitable shank 8, which may 80 preferably be cylindrical in form, the extremity of the shank being of slightly less external diameter than that portion nearer the brush-head 5, so as to form a shoulder 9. 90 The shank may be fixedly secured to the brush-head in any desired manner, and is provided on its upper side with a longitudinal, preferably oblong, slot 11 for a purpose 95 to be hereinafter described.

Pivoted adjacent to the tubular portion or socket 2 of the handle, is the catch 15, which may preferably be formed of sheet metal substantially in the shape shown. This catch is substantially semi-cylindrical in 100 cross section, and is pivoted to the handle 1 by means of a horizontal pivot 16, passing through the socket 2 and through dependent 105 backwardly extending portions of the catch so that the latter may be rotated about the pivot 16 in a substantially vertical plane.

The forward portion of the catch, that is, the portion nearest the brush-head, may preferably be provided with depending portions or ears 20, of such length that they will 5 extend slightly below the point of greatest interior diameter of the catch, which preferably is approximately equal to the exterior diameter of the socket 2 of the handle. The catch may preferably be provided with a centrally disposed downwardly projecting dog 24, which may preferably be formed integral with the body of the catch by cutting the metal composing the same in such manner that the dog may be bent inwardly substantially 10 to the center of the catch as shown, so that it will lie substantially in a vertical plane passing through the central longitudinal axis of the socket 2. Of course the dog may be formed separately from the body of the catch and secured thereto by solder or riveting or in any other desired manner, but in practice it has been found preferable to form it integral with the body of the catch in the manner described. The forward end 15 of the catch if desired may be slightly turned up to form the thumb piece 26.

The socket 2 of the handle is provided on its upper side with a suitable preferably oblong, slot 28, of a length and width slightly 20 greater than the respective length and thickness of the dog 24, and so disposed with relation to the catch 15, that when the same is rotated about its pivot 16, to assume the position shown in Fig. 1, the dog 24 will enter 25 the slot 28 and project therethrough into the interior of the socket 2. If, while the catch is in the position shown in Fig. 2, the shank 8 of the brush-head 5 be inserted in the socket 2 of the handle 1, the shank 8 being 30 of a diameter to form a nice fit within the socket, and the shoulder 9 being operative to limit the distance it may be inserted therein, and the slot 11 alined with the slot 28, it will 35 be evident that when the catch is closed to the position shown in Fig. 1, the dog 24, will pass through both the slot 28 and the slot 11, the latter being of a suitable size to form a nice fit in all directions with the dog 24. Furthermore, the catch 15 will be securely 40 maintained in closed position as shown in Fig. 1 by the engagement of the ears 20 with the exterior of the socket 2, which, as already stated, are of sufficient length to come slightly below the point of greatest 45 diameter of the socket 2 and thus partially surround the same, while, however, being so adjusted as to be capable of being forced or sprung past the point of greatest diameter of the socket 2 when the catch is opened or 50 closed by the operator. The former operation may readily be accomplished by pressing down upon the catch when in the position shown in Fig. 2, and the latter, by inserting the thumb-nail beneath the thumb piece 26

and raising the catch out of its closed position, as shown in Fig. 1.

It will thus be evident that the brush-head is securely maintained in operative position upon the handle when the catch is in closed position, and is prevented both from 70 rotative movement about the central longitudinal axis of the socket 2, as well as from longitudinal movement with relation to the handle 1, while, however, being capable of ready detachment from the handle by raising the catch 15, thus permitting it to be disposed within the handle, where the bristles will be protected and kept from contact with foreign substances. At such times the catch is generally left in closed position 80 from which it is raised to permit the insertion of the shank 8 when it is desired to place the brush-head in operative position upon the handle.

While I have herein described my invention as applied in connection with a toothbrush, it will be evident that the use to which the brush may be especially adapted is immaterial, and that the invention may be applied with equal success to other 90 brushes, such as nail brushes. Furthermore, I do not desire to limit my invention to the exact form herein shown and described, as it will be evident that various changes may be made in the details of construction and 95 arrangement of the various parts of the device, without departing from the spirit and scope of the invention as defined in the appended claims.

Having thus described my invention, I 100 claim and desire to protect by Letters Patent of the United States:—

1. In a toothbrush, the combination with a handle having a space adapted to contain the brush-head and an outwardly extending cylindrical socket, of a detachable brush-head having a shank provided with a slot, and means movable upon said handle adapted to partially surround said socket and having a depending portion adapted to enter said slot when the brush-head is in operative position upon said handle.

2. In a toothbrush, the combination with a handle having a space adapted to contain the brush-head and an outwardly extending portion forming a cylindrical socket provided with a slot, of a detachable brush-head having a shank adapted to enter said socket and also having a slot, and means having a downwardly depending dog, pivotally mounted upon said handle and adapted to embrace said socket, said dog being operative to enter said slots and prevent longitudinal or rotative movement of said brush-head with respect to said handle when 125 said handle is in operative position thereon.

3. In a brush, the combination of a handle forming a casing for the brush-head when

not in use, a detachable brush-head, and my hand this 19th day of November, A. D. means separate from said handle pivotally 1913.
mounted thereon and adapted to partially
embrace said handle operative to maintain
said brush-head fixedly positioned upon said
handle.

In witness whereof I have hereunto set

ERNEST S. GOLDY.
